CLAIM

The ornamental design for a saddle, as shown and described.

DESCRIPTION

FIG. 1 is a perspective view of a saddle showing my new design;
FIG. 2 is top plan view thereof;
FIG. 3 is a front elevation view thereof;
FIG. 4 is a right side elevation view thereof, the left side elevation view being a mirror image;
FIG. 5 is a rear elevation view thereof;
FIG. 6 is a bottom plan view thereof;
FIG. 7 is a perspective view of a first alternative embodiment thereof similar to that of the embodiment of FIG. 1 with the thigh block shown in FIGS. 1-6 removed;
FIG. 8 is top plan view of the first alternative embodiment;
FIG. 9 is a front elevation view of the first alternative embodiment;
FIG. 10 is a right side elevation view of the first alternative embodiment, the left side elevation view being a mirror image;
FIG. 11 is a rear elevation view of the first alternative embodiment;
FIG. 12 is a bottom plan view of the first alternative embodiment;
FIG. 13 is a perspective view of a second alternative embodiment thereof similar to that of the embodiment of FIG. 1 with the flap shown in FIGS. 1-6 removed;
FIG. 14 is top plan view of the second alternative embodiment;
FIG. 15 is a front elevation view of the second alternative embodiment;
FIG. 16 is a right side elevation view of the second alternative embodiment, the left side elevation view being a mirror image;
FIG. 17 is a rear elevation view of the second alternative embodiment; and,
FIG. 18 is a bottom plan view of the second alternative embodiment.
The broken lines shown in the drawings of FIGS. 1-18 represent portions of the saddle that form no part of the claimed design.
The jagged-line surface shading in the figures represent leather while the stippling pattern in the FIGS. 1, 2, 4, 7, 8, and 10 represents a looped fabric surface.
